WALL SUPPORTED SHOE HOLDER AND STRETCHER

Arnold A. Hansen, Des Plaines, Ill.

Application March 1, 1955, Serial No. 491,247

5 Claims. (Cl. 12—128.6)

This invention relates to combined shoe holders and stretchers and more particularly to a combined shoe holder and stretcher which is capable of effectively holding shoes for shining, cleaning and the like, and stretching shoes of widely varying sizes and previous conditions of stretch.

Prior to this invention, shoe holders of this general type were inadequate in that the mechanical means employed for holding a shoe of a predetermined size or stretching a shoe to a predetermined size were capable of only step-by-step adjustment. These prior art devices were further characterized in that a pair of arms was provided one of which was movable and was fastened in a predetermined position of adjustment by a frictional contact of a limited area. Furthermore, in these prior art devices the force necessary to hold or stretch a shoe was supplied almost entirely by the user. While devices of this type were known which provided for selective mounting of a plurality of shoe trees to accommodate shoes of varying characteristics, none of the trees could be conveniently mounted or replaced because of the use of thumbscrews and the like. A disadvantage of these devices is that they are cumbersome in operation, and the shoe tree is often inadvertently removed with the shoe.

Accordingly, a principal object of the invention is to provide a combined shoe holder and stretcher in which means are provided for holding securely shoes of varying sizes and for stretching a shoe to a predetermined desired size.

A further object of the invention is to provide a device of the stated type in which a plurality of shoe trees of varying conformations are selectively mountable with ease and convenience.

Another object of the invention is to provide a device of the stated character which may be manufactured economically and which is characterized by resistance to periodic stresses and strains incident to the buffeting motions employed in shining operations.

A more particular object of the invention is to provide a device of the mentioned type which includes a bracket adapted to be affixed to a wall or other vertical surface, a bracket arm removably attached to the bracket, a shoe tree releasably attached to the bracket arm, an elongated screw rotatably mounted on the bracket arm, a heel post threadably arranged on the screw, and a heel plate affixed to the heel post for engaging the heel portion of a shoe, the front end of which is mounted on the shoe tree. By this arrangement, shoes may be mounted in a manner that all parts are readily accessible. The forepart of the bracket arm is formed with a knee from which extends vertically a foot portion which then curves outwardly to form a support for the tree. When the tree is in position for use, the shoe mounted thereon is securely supported from toe to heel.

These and other objects, advantages and features of the present invention will be apparent to those skilled in the art from the following description taken in conjunction with

2

the accompanying drawings in which similar reference characters relate to similar parts, and in which:

Fig. 1 is an elevational view, partly in section and partly broken away for the sake of clarity, of a combined shoe holder and stretcher made in accordance with the present invention;

Fig. 1a is a view in perspective of the bracket of Fig. 1;

Fig. 2 is a plan view of the device of Fig. 1, broken away in part to show the details of certain of the elements;

Fig. 3 is an elevational view of the bracket arm of the combined shoe holder and stretcher of the present invention, and a pair of shoe trees of varying sizes each of which may be selectively mounted thereon;

Fig. 4 is an enlarged elevational view, in section, taken substantially on line 4—4 of Fig. 1;

Fig. 5 is an elevational view in section, taken substantially on line 5—5 of Fig. 1;

Fig. 6 is a vertical sectional view taken substantially on line 6—6 of Fig. 1;

Fig. 7 is an elevational view, partly in section, of a modified form of the present invention;

Fig. 8 is a plan view, partly broken away for the sake of clarity, of the form of the invention shown in Fig. 7;

Fig. 9 is an elevational view, partly in section, of another modified form of the present invention;

Fig. 10 is an enlarged elevational view, in section, taken substantially on line 10—10 of Fig. 9; and

Fig. 11 is an enlarged fragmentary elevational view of the bracket arm of the form of the invention shown in Fig. 9.

With reference to the drawings and more particularly to Fig. 1, the combined shoe holder and stretcher of the present invention comprises essentially a bracket 10 adapted to be secured by means of screws 11 to a wall or other vertical surface, a tapered socket 12 forming a part of the bracket, a bracket arm 13 having at one end a flange 14' tapered to correspond to the shape of the socket 12 and at the other end an integrally formed foot portion 14 upon which are selectively mounted a plurality of shoe trees 15, a heel post 16 movable longitudinally of the bracket arm 13 by means of an elongated screw 17 which is actuatable by a knurled knob 18.

According to the present invention, means are provided for efficiently and effectively substituting one shoe tree for another so that shoes of widely varying characteristics may be accommodated. To this end, the foot portion 14 is constructed and arranged slidably to receive a shoe tree in a manner that engagement and disengagement of these elements are readily effected and relative displacement while in use is precluded. In particular, the foot portion 14, which like the bracket arm 13 is of channel cross-section extends vertically from a knee 13' formed at the outer end of the bracket arm, and then outwardly to form a support for one of the shoe trees 15, and is provided with depending parallel arms 19 and 22. Advantageously, the construction of foot portion 14 and of the shoe tree 15 is such that the tree may be extended to a sufficient height for it to form a backing and support for the tongue and upper last of the shoe, thereby facilitating cleaning and shining these shoe portions. Extending inwardly from the arms 19 and 22 are a pair of flanges 23 and 24. At one end of each of the flanges 23 and 24 is formed a tang 25 which extends substantially perpendicularly to the plane of the flanges. The gap between the tangs 25 is sufficiently narrow to permit the forming of an aperture 26, as best shown in Figs. 2 and 4. A spring clip 27 has a portion 28 secured to the tangs 25 by means of a fastening element 29 received in the aperture 26. Portion 32 of the clip 27 is normally spaced from flanges 23 and 24 to permit the insertion of a channel section 35 hereafter described.

Desirably, the shoe trees 15 are of two sizes, one size for women's and children's shoes, and a larger size for men's shoes, as best shown in Figs. 3. Each of the trees 15 is provided with a transversely extending structural member 34 having a channel section 35, whose internal dimensions correspond substantially to the external portion of the foot portion 14, so that the latter may be inserted into the former. The outer ends of the member 34 are provided with depending flanges 36 for securing the member in position on the inner surface of the shell of the tree. The foot portion 14 fits snugly within the channel 35 and is retained in this position by the spring clip 27, as will be understood. To relieve the clip 27 of the forces resulting from the pressure employed to shine the shoes, ridges 35a are formed throughout the length of the channel section 35, and complementary grooves 19a and 22a are formed in the arms 19 and 22 respectively, corresponding in length to said ridges 35a.

The details of the bracket 10 are shown clearly in Fig. 1a. This bracket is of unitary construction and includes a tapered base plate 10, having extensions 10a at the side edges which form the tapered socket 12. To permit easy reception of the flange 14' in the socket 12 even in the event that some of the screws 11 are not properly seated, a pair of embossments 12a are formed in the base plate 10 to maintain the flange 14' in spaced relation to the surface of the base plate 10.

With reference now to Figs. 1, 5 and 6, the screw 17 is centrally mounted within the channel of the bracket arm 13 by means of an L-shaped bracket 37, which is apertured for reception of one end of the screw. The screw is provided with a shoulder at each end to prevent axial movement either to the right or to the left as viewed in Fig. 1. The heel post 16 is provided with a head portion 38 shaped to conform to the configuration of the channel of the bracket arm 13. By this arrangement, rotation of the heel post with respect to the bracket arm 13 is prevented. The head portion 38 is provided with a threaded aperture for reception of the screw 17, as will be understood. The heel post 16 is formed integrally with the head portion 38, and is threaded at its lower end for reception of the heel plate 39, which is shaped to conform to the inside of the heel of the average shoe. By this arrangement, the heel post 16 may be moved to the right as viewed in Fig. 1, by turning the hand knob 18, and the heel plate 39 may be moved with respect to the heel post 16 to accommodate shoes of varying heel heights.

In operation, the spring clip 27 is first manually depressed, and then the channel 35 of the cross-member 34 is aligned with the channel of the foot portion 14. The tree is then moved to the right, as viewed in Fig. 1, until the limiting position is reached, at which position the spring clip 27 returns to its normal position, with the result that the hook 33 functions as a locking device to retain the tree on the foot portion. A shoe may be mounted on the present device by positioning the shoe with the hands so that the tree enters the toe section and forepart of the shoe as far as it goes, then pulling the rear part of the shoe up so that the heel plate 39 engages the inside of the shoe at the heel. The shoe is then held momentarily with one hand while the knurled knob 18 is rotated with the other hand. Turning of the hand knob advances the heel post to the right, thus effecting tightening of the shoe with its forepart and heel stretched respectively between the tree and the heel post. Should stretching be desired, the screw 17 is merely advanced a predetermined distance. The tree is readily removable by depressing hook 33 and moving the tree to the left as viewed in Fig. 1.

In Figs. 7 and 8 is shown a modified form of the invention in which a spring clip 27a is provided which is substantially U-shaped in configuration, and which is provided at each end with a hook 33a. The arms 19 and 22

of the foot portion 14 are apertured at 42 for reception of the hooks 33a. In this instance, the walls of the channel 35 are correspondingly apertured so that the ends of the hooks 33a may protrude therethrough. In this form of the invention there is no need to depress the clip 27a to mount the tree. The tree is merely brought into alignment and urged into engagement with the foot portion. The sides of the channel 35 ride up over the sloping portions 33a of the clip as the spring deflects inwardly. To remove the tree, the hooks 33a are depressed inwardly to free them from engagement with apertures 42, and the tree is removed as before.

With reference now to Figs. 9, 10 and 11, the form of the invention disclosed in these figures comprises an integrally formed bracket arm 13a, having a solid foot portion 14a. A spring clip 27, of the type utilized in the form of the invention shown in Fig. 1, is secured in position by a fastening element 29a. Ridges 35a are formed in the mouth of channel 35, as hereinbefore described, and complementary grooves 14b, similar to grooves 19a and 22a, are formed in solid foot portion 14a to relieve clip 27 of pressure which may result when shining the shoes. The main portion of the bracket arm 13a is channel-shaped and includes an integral bracket 37a apertured for the reception of the elongated screw.

In the above described invention a combined shoe holder and stretcher is provided in which shoe trees of different sizes may readily be mounted and dismounted for the accommodation of shoes of different sizes. The provision of the screw mechanism permits a great number of gradations of the heel post with respect to the foot portion. By this arrangement, shoes of different sizes may be held in position for shining or cleaning, and shoes may be stretched to any desired size. The heel plate 39 is desirably threadably mounted on the heel post 16, so that it may be readily raised to a position to accommodate shoes of the high heel type. This invention may be embodied in constructions which differ in many respects and details from the particular embodiments disclosed. Other modifications which do not go beyond the scope of the invention will readily project themselves to those skilled in the art. It is, therefore, not intended that the invention be limited to the exact construction shown and described, but only to the inventive concept as defined in the appended claims.

I claim:

1. A combined shoe holder and stretcher comprising, in combination, a mounting bracket adapted to be attached to a wall or other vertical surface, a bracket arm of channel cross-section removably secured to said bracket, an elongated screw rotatably mounted within said bracket arm, said bracket arm having a foot portion of channel construction, a pair of inwardly directed flanges formed integrally with said foot portion, a tang extending perpendicularly to each of said flanges, a shoe tree mounted on said foot portion, a spring clip secured to said tangs and operative to retain said shoe tree in position for use, and a heel post threadably mounted on said screw and operative upon rotation of said screw firmly to grasp a shoe for shining, cleaning or the like.

2. A combined shoe holder and stretcher comprising, in combination, a mounting bracket adapted to be attached to a wall or other vertical surface, a bracket arm of channel cross-section removably secured to said bracket, an elongated screw rotatably mounted within said bracket arm, said bracket arm having a foot portion of channel construction, a pair of inwardly directed flanges formed integrally with said foot portion, a pair of grooves in said foot portion, a shoe tree mounted on said foot portion, said shoe tree including a transversely extending structural member having a centrally disposed channel in which the foot portion is received, said structural member being provided with ridges at the mouth of the centrally disposed channel complementary to said grooves and corresponding in length thereto, a tang ex-

tending perpendicularly to each of said flanges, a spring clip secured to said tangs and operative to retain said shoe tree in position for use, and a heel post threadably mounted on said screw and operative upon rotation of said screw firmly to grasp a shoe for shining, cleaning or the like.

3. A combined shoe holder and stretcher for use with a wall mounted supporting bracket, comprising: a bracket arm of channel cross-section removably secured at one end to said bracket; an elongated screw rotatably mounted within said bracket arm; means whereby said screw is rotated; a knee portion at the other end of said bracket arm; a foot portion of channel cross-section extending downwardly and outwardly from said knee portion; a shoe tree; a centrally disposed channel on the underside of said shoe tree for slidably receiving said foot portion in nested relationship; a pair of grooves, one in each leg of the channel cross-section forming said foot portion and coextensive with the length thereof; a pair of ridges at the mouth of the centrally disposed channel, complementary to said grooves, corresponding in length thereto, and cooperable therewith whereby said tree is secured against accidental dislodgment by pressure applied perpendicularly thereto; a spring clip connected with the channel of said foot portion and operative on said centrally disposed channel whereby said tree is secured against sliding off said foot portion; means whereby said clip is operable to release said tree from said foot portion; a heel post threadably mounted on said screw; and a heel plate threadably mounted on said heel post whereby shoes of various heel heights may be firmly engaged by said heel plate and tree for shining, cleaning or the like.

4. A combined shoe holder and stretcher comprising: a bracket mountable on a vertical surface; a bracket arm removably secured at one end to said bracket; an elongated screw rotatably mounted in said bracket arm; means whereby said screw is rotated; a foot portion at the other end of said bracket arm, said foot portion formed with a pair of grooves, one on each side thereof and corresponding in length thereto; a shoe tree; a centrally disposed channel on the underside of said shoe tree

for slidably receiving said foot portion; a pair of ridges at the mouth of said channel, one for each of said grooves, corresponding in length thereto, and cooperable therewith to retain said tree on said foot portion despite the application of downward pressure on said tree; a stop on said foot portion limiting the slideable positioning of said tree thereon; a spring clip connected with said foot portion and operative on said channel to retain said tree against sliding off said foot portion; means whereby said clip is operable to release said tree from said foot portion; and a heel post threadably mounted on said screw and operative upon the rotation of said screw firmly to grasp a shoe for shining, cleaning or the like.

5. A combined shoe holder and stretcher comprising: 15 a bracket mountable on a vertical surface; a bracket arm removably secured at one end to said bracket; an elongated screw rotatably mounted in said bracket arm; means whereby said screw is rotated; a foot portion of channel cross-section fixed to the other end of said bracket arm; a shoe tree; a centrally disposed member of channel cross-section carried on the underside of said shoe tree; retaining means on said foot portion, said retaining means having parallel walls forming a substantially horizontal track to guide said member thereon; rail means 20 on said member, corresponding in length to said retaining means, and cooperable therewith whereby said tree is horizontally slidably guided onto said foot portion and secured against accidental dislodgment and lateral turning by pressure applied perpendicularly thereto; a spring clip connected with said foot portion and operative on the channel of said tree whereby said tree is releasably secured against sliding from said foot portion; and a heel post threadably mounted on said screw and operative upon rotation of said screw firmly to grasp a shoe for 25 shining, cleaning or the like.
